(57) **CLAIM**

The ornamental design for a moisture analyzer, as shown
and described.

DESCRIPTION

FIG. 1 is a perspective view of the top, front and right side
of a moisture analyzer showing my new design;
FIG. 2 is a right side elevational view thereof;
FIG. 3 is a left side elevational view thereof;
FIG. 4 is a front elevational view thereof;
FIG. 5 is a rear elevational view thereof;
FIG. 6 is a top plan view thereof;
FIG. 7 is a bottom plan view thereof;
FIG. 8 is a view similar to FIG. 1 with a cover retracted;
FIG. 9 is a right side elevational view thereof;
FIG. 10 is a left side elevational view thereof;
FIG. 11 is a front elevational view thereof; and,
FIG. 12 is a top plan view thereof.
